UNITED STATES PATENT OFFICE.

WALTER WILFRID DARNILL, OF LEICESTER, ENGLAND, ASSIGNOR TO UNITED SHOE MACHINERY COMPANY, OF PATERSON, NEW JERSEY, A CORPORATION OF NEW JERSEY.

GRIPPER MECHANISM FOR PULLING-OVER MACHINES.

1,163,588.

Specification of Letters Patent.

Patented Dec. 7, 1915.

Application filed March 2, 1914. Serial No. 821,993.

To all whom it may concern:

Be it known that I, WALTER WILFRID DARNILL, a subject of the King of England, residing at Leicester, Leicestershire, England, have invented certain Improvements in Gripper Mechanisms for Pulling-Over Machines, of which the following description, in connection with the accompanying drawings, is a specification, like reference 10 characters on the drawings indicating like parts in the several figures.

This invention comprises improvements in or relating to pulling-over or like machines and relates particularly to machines 15 of the type described and shown in prior United States Letters Patent No. 1,030,522, granted June 25, 1912, on application of Ronald F. McFeely. In machines of this type there are provided a gripper for the 20 toe of the shoe and two grippers for each side of the shoe and operating mechanism for drawing the grippers upwardly to pull the upper over the last. The grippers of each of the side gripper mechanisms are 25 mounted side by side in a single carrier and the gripping faces of one gripper are substantially in alinement with the gripping faces of the other gripper. It has been found that owing to the curvature of the 30 last the gripping faces of the rear gripper do not lie parallel to that portion of the last which they are opposite, and consequently the upper cannot be readily engaged by the grippers, a difficulty which it is an object of the present invention to overcome. Furthermore with the gripping faces of both 35 grippers in alinement the upper is not pulled over the last in an even fashion but is subjected to local stress. In accordance with 40 the present invention these difficulties are overcome by providing for a pulling-over or like machine comprising a plurality of side grippers preferably connected with a single operating mechanism, an arrangement of the said grippers wherein the gripping faces of one gripper and the gripping faces of the other gripper are at an angle to one another, so that the gripping faces 45 of each gripper shall lie in a position substantially parallel with that part of the last

which each is opposite. In a convenient embodiment of the invention this is carried into effect by constructing the rear grippers so that their gripping faces are twisted, with relation to the mechanism that carries them, 55 through an angle such that when the gripping faces of the front grippers are in a position substantially parallel to the portion of the last which they are opposite the gripping faces of the rear grippers will also be 60 substantially parallel to that part of the side of the last which they are opposite. Preferably also while the front grippers will have on the gripping faces of their jaws lines of corrugations formed as usual to 65 extend substantially parallel with the bottom of the forepart of the last, the rear grippers will have on their gripping faces lines of corrugations inclined downwardly and backwardly at an angle to those on the 70 front grippers for the purpose of better seizing and holding the upper extending toward the shank of the shoe. The rear jaws may have their lower edges inclined downwardly and backwardly relatively to the 75 plane of the forepart of the shoe bottom for the same purpose.

While the invention has been described as embodied in a construction wherein the back jaws are twisted relatively to their carrying mechanism it is to be understood that it is not limited to this precise construction, for it is within the scope of the invention to form the gripping faces on parts 80 separate from the rest of the gripper, the parts being locked together by any suitable means so that the gripping faces can be adjusted into a position substantially parallel to that portion of the last which they are opposite.

The features of the invention will appear more fully in connection with the following description of a preferred embodiment thereof illustrated in the accompanying drawings and the invention will be particularly pointed out in the claims at the end of the description.

Figure 1 shows the machine of said prior patent equipped with this invention. Fig. 2 shows in plan view the relation of the 95 100

grippers to the edge of the last as provided for by this invention. Fig. 3 shows the new gripper jaws in perspective, and Fig. 4 shows one jaw in side elevation.

5 The construction of the pulling-over machine, Fig. 1, may be as a whole substantially like that shown in the prior patent and well known in the art and the operating mechanism for the grippers may also be like that shown. There is one gripper at the toe and two grippers for engaging each side of the shoe, each side gripper mechanism comprising front and rear pairs of jaws 1, 2, 3 and 4 of which the jaws 1 and 3 are fixed upon their carriers 5, 6 and the jaws 2 and 4 are pivoted to said carriers, and an operating bar 8 extending to a cam operated lever 10 has connection with both carriers 5 and 6 for closing and uplifting the jaws. There 10 is preferably an equalizing or compensating connection, not shown, between the front and rear grippers to permit the relative movement that is desirable because of the differences in shape of the portions of the 15 last over which extend the respective belts of upper to the ends of which the front and rear grippers on the opposite sides of the last are connected for pulling over.

20 The gripping faces of the rear pair of jaws 3, 4 and the gripping faces of the front pair of jaws 1, 2 are at an angle to one another, as shown best in Fig. 2, so that the gripping faces of each shall lie in a position substantially parallel with that part of the 25 last side or edge to which each is opposite, as is clearly indicated in Fig. 2. This arrangement is effected by constructing the 30 rear gripper so that its gripping faces are twisted, as shown in Fig. 2, with relation to 35 their carriers 6, through an angle such that 40 when the gripping faces of the front gripper are in a position substantially parallel to the edge or side of the ball portion of the 45 last to which they are opposite the gripping 50 faces of the rear gripper will be inclined rearwardly and inwardly substantially parallel to that adjacent portion of the edge of the last which extends toward the shank. Also preferably and as shown best in Fig. 4, 55 while the front gripper has corrugations on its gripping faces that extend in lines substantially parallel to the plane of the forepart of the last the rear gripper has lines of 60 corrugations which are inclined downwardly and backwardly relative to those on the front gripper for better seizing and pulling the upper extending toward the shank of the shoe. The rear jaws may also have their gripping faces correspondingly inclined down- 65 wardly and backwardly as indicated by the direction of the lower edge of jaw 3 in Fig. 4, so as better to reach the upper extending toward the shank which they are to seize.

Having explained this invention, its pur-

pose, and the preferred construction embodying the same, I claim as new and desire to secure by Letters Patent of the United States:—

1. A pulling-over machine having in combination, two grippers for engaging adjacent portions of stock, and suitable operating mechanism including means to effect up-draw movement of the grippers and constructed and arranged to permit relative movement of the two grippers during the up-draw, said grippers comprising pairs of jaws of which one jaw of each pair is pivoted and the gripping faces of the jaws of one pair are at an angle to the gripping faces of the jaws of the other pair. 70

2. A pulling-over machine having, in combination, suitable operating mechanism, two grippers for engaging the same side of the shoe, and a single actuator for effecting the operation of said grippers, one gripper being adapted to engage the upper at the side of the ball near the tip seam and the other near the incurve of the last edge leading to the shoe shank, said latter pair of jaws having its gripping faces angled relatively to the other pair and fixed in such relative angular relation to adapt it to pull relatively to the adjacent curved edge of the last in approximately a uniform manner with the other pair of jaws. 90

3. A pulling-over machine having in combination, suitable operating mechanism, two grippers for engaging stock on the same side of the shoe, and a single actuator for said grippers, the rear gripper having its gripping faces twisted with respect to the gripping faces of the front gripper and inclined obliquely downwardly and rearwardly relatively to the plane of the last bottom. 100

4. A pulling-over machine having in combination, suitable operating mechanism, two grippers for engaging adjacent portions of stock and a single actuator for said grippers, each of said grippers comprising two cooperating jaws, one of which is pivoted and the gripping faces of one pair of jaws lying in a plane at an angle to the axis of its pivot. 110

5. A pulling-over machine having, in combination, suitable carrying and operating mechanism, and front and rear pairs of side grippers, the front pair having lines of corrugations on its gripping faces arranged to extend substantially parallel with the plane of the last bottom and the rear pair of jaws having lines of corrugations on its gripping faces inclined downwardly and backwardly at an angle to those on the front pair. 120

6. A pulling-over machine having, in combination, suitable carrying and operating mechanism, and front and rear pairs of side grippers, the front pair of jaws being

substantially parallel with the plane of the shoe bottom and the rear pair of jaws having their gripping faces extending downwardly and backwardly relative to the front 5 pair for the purpose described.

In testimony whereof I have signed my

name to this specification in the presence of two subscribing witnesses.

WALTER WILFRID DARNILL.
